UNITED STATES PATENT OFFICE

OSCAR BOTO SCHELLBERG, OF NEW YORK, N. Y.

VALVE MECHANISM FOR PROCTOTHERAPY APPARATUS

Application filed January 30, 1929. Serial No. 336,124.

This invention relates to proctotherapy apparatus of the class disclosed in my Patent No. Re. 16,251 dated January 12, 1926, and more particularly to an improved valve construction for use in such apparatus.

Among the principal objects which the present invention has in view are: To provide an improved three-way valve arranged so that the same may be quickly dismantled or 10 disassembled for sterilizing after use, and reassembled for treating another patient, reducing the time between treatments to a minimum; to provide an improved valve construction which will control the admission of 15 one or more fluids through the inlet passage to the injector tube and when turned to the exhaust position will permit the fluids discharged through the injector tube to drain back through the outlet or discharge passage 20 in the valve to a waste receptacle, thereby never permitting any portion of the valve through which the clean unused fluid passes to come in contact with that portion of the valve used for discharging the polluted fluid; 25 and to provide visual means on the valve to indicate the position of the valve ports. Other objects will appear as the description proceeds.

Drawings

Figure 2 is a side elevation of my valve and assembly with a portion thereof broken away;

35 Figure 3 is a transverse sectional view through the valve casing, showing the valve body in elevation;

Figure 4 is a bottom plan view of the valve showing the spring washer;

40 Figure 5 is a sectional view through the valve taken on the line 5-5 of Figure 3; and

Figure 6 is a schematic perspective showing 45 of the valve connected for use in proctotherapy.

Description

In carrying out my invention, I provide a valve casing 10 having a conical interior 50 wall or seat and three integrally connected

tube connections 11, 12 and 13, for connection with the fluid supply, the outlet or injector connection, and the drain or waste connection, respectively. The outer end of the injector connection 12 is provided with a 55 resilient clamping member 14 for holding the flexible tubing attached to the injector nozzle in fixed position thereon. The drain connection 13 is bent downwardly to facilitate the discharge of the polluted waste fluid, while the supply connection 11 is exteriorly 60 threaded at 15 for attachment with an arm or branch 16 of the three-way fitting 17, each branch of which is controlled by separate valves 18, 19 and 20, and in turn are connected with containers 21, 22 and 23, containing 65 water and one or more medicated fluids. A wing nut 24 swivelly mounted at the outer end of the arm 16 of the fitting 17 is adapted to thread on to the threaded portion 15 of the connection 11 to hold the said parts in 70 rigid coupled position. A supporting arm 24^a is connected with the fitting 17 and serves to support the valve assembly and fitting to 75 the table 25 upon which the patient is placed.

The valve body 26 is conical in shape and is adapted to fit snugly within the conical seat in the casing 10, and is provided with a pair of spaced parallel passages 27 and 28, respectively for the clean fluid and for the 80 used or waste fluid, which passages are adapted to register with the fluid supply connection and injector connection, and the injector connection and the waste or drain connection. An operating handle 29 extends upwardly 85 from the valve body 26 for moving the same as desired. A cylindrical shank 30 extends downwardly from the lower surface of the body 26 and terminates in a reduced threaded portion 31. The rigid washer 32 is adapted 90 to fit over the shank 30 and to seat on the lower face of the valve casing 10, and is securely held thereon by a resilient washer 33 having a plurality of spring fingers of said washer 33 engageable with the said washer 32, and 95 forced thereagainst under tension by the locking nut 34 on the threaded portion 31 of the shank 30.

A quadrant 35 is secured between the connections 12 and 13 and is provided with 100

spaced lugs for limiting the throw of the valve, and cooperates with an indicating finger 36 carried by the valve body 26, and serves to indicate the position of the passages in the said valve.

It is therefore apparent that after a patient has been treated, it becomes necessary to thoroughly sterilize all parts of the valve and its associated assembly or fittings before the same may again be used for another patient. By unscrewing the wing nut 34^a and the locking nut 34, the valve may be quickly disassembled and placed in a sterilizing device, and all parts thereof positively sterilized, thereby preventing any infection being transmitted from one patient to another.

It will further be seen that the desired flow and mixture of the fluids may be easily regulated to efficiently treat the patient.

Many minor changes in detail of construction may be resorted to without departure from the spirit of the invention.

Claims:

1. A valve mechanism as characterized comprising a swinging bracket member having a fitting embodying multiple receiving passages converging into a single delivery passage, and a valve assembly embodying a cup-like casing having a plurality of tubular extensions, one of which being a receiving passage, is adapted for operative connection with said delivery passage on said swinging bracket, said assembly further embodying a rotatable valve body having a plurality of passages therethrough adapted to register the one with said receiving passage and simultaneously with one of said tubular extensions, and the other passage being adapted to register with said receiving passage and the other tubular extension when moved thereto; and means readily operable for operatively connecting and releasing said casing and said bracket, and separate means readily operable to operatively connect said casing and said valve body.

2. A valve mechanism as characterized comprising a swinging bracket member having a fitting embodying multiple receiving passages converging into a single delivery passage, and a valve assembly embodying a cup-like casing having a plurality of tubular extensions, one of which being a receiving passage, is adapted for operative connection with said delivery passage on said swinging bracket, said assembly further embodying a rotatable valve body having a plurality of passages therethrough adapted to register the one with said receiving passage and simultaneously with one of said tubular extensions, and the other passage being adapted to register with said receiving passage and the other tubular extension when moved thereto; and means readily operable for operatively connecting and releasing said casing and said bracket, said means consisting of a wing nut,

and means readily operable for operatively connecting said casing and said valve body, said second mentioned means embodying a spring seated washer bearing on said casing to close the same and to secure the valve body firmly in said casing.
